UNITED STATES PATENT OFFICE.

EARL E. BERRY, OF BELOIT, WISCONSIN, ASSIGNOR TO BELOIT IRON WORKS, OF BELOIT, WISCONSIN, A CORPORATION OF WISCONSIN.

VACUUM PIPE CONNECTION FOR CYLINDER MACHINES.

Application filed June 13, 1923. Serial No. 645,028.

My invention relates to paper making machines, and especially to machines known as cylinder type machines.

One of the objects of the invention is to provide a simple and practical construction of machine of the class specified.

Another object of the invention is to arrange for the advantageous application of suction to the cylinder and also to arrange for the ready adjustment of the pressure of same as desired.

Another object of the invention is to arrange for the withdrawal of water from cylinder by suction.

Another object of the invention is to permit independent regulation of the suction for forming and drying the paper on the same cylinder and for withdrawing the water.

In the accompanying drawings, Fig. 1 is a longitudinal section of a paper making machine embodying my invention;

Fig. 2 is a plan view of same.

Referring to the drawings, I show a rotary cylinder 1 having a perforate cylindrical wall adapted for forming paper.

The cylinder 1 is mounted on a fixed tubular shaft 3, supported at its ends by pedestals 4 and 5. Shaft 3 has upstanding tubular members 6—6 and downwardly extending members 7—7. The former are for exhausting air from the upper part of the cylinder 1 to form and dry the paper. The latter (members 7—7) are for exhausting air from the lower part of the cylinder for withdrawing water therefrom—water which is withdrawn from the pulp material in the formation and drying of the paper.

The tubular members 6—6 are connected with the upper longitudinal section or compartment 9 of shaft 3; the members 7—7 with the lower compartment 10 thereof. Compartment 9 is connected with chambers 11 and 12 in pedestals 4 and 5, and compartment 10 with chambers 13 and 14 in same.

Air pipes 15 and 16 are connected with chambers 11 and 12 respectively. Air pipes 17 and 18 are connected with compartments 13 and 14, respectively. Air pipes 15 and 17 are preferably connected together, as are 16 and 18, and all run to a suitable suction pump 20. Pipes 15, 16, 17 and 18 are provided with valves 21, 22, 23 and 24, respectively, so that air pressure in each pipe may be independently regulated. Water dis-

charge pipes 25 and 26, extend from chambers 13 and 14, respectively, and are connected to a suitable pump 27, which is also connected with a head box 28 for supplying paper material to cylinder 1. A plate or box, (not shown) is located within cylinder 1, opposite the apertures therein, between the take-off of the paper and the point of application of the pulp, to prevent air from entering and destroying the vacuum.

In operation, paper material is fed from head box 28 to vat 29 containing cylinder 1, so that such material may be applied to the lower portion of cylinder for forming paper thereon. The arrangement for doing this is shown in my copending application Serial No. 630,484, filed April 7, 1923, and is not described herein as it forms no part of my present invention. The paper material adheres to the cylinder as same revolves, being formed thereon and dried by the suction in upper part of cylinder controlled by pipes 6—6. The water withdrawn from paper material drops to the bottom of cylinder and is lifted by suction of pipes 7—7 and siphoned into compartments 13 and 14, whence it is withdrawn by pipes 25 and 26 and then returned to head box 28 for further use.

Ordinarily air pressure in 10, 13 and 14 is reduced somewhat more than in 9, 11 and 12, so as to secure the proper action. Regulation of pressures may be secured by valves 21, 22, 23 and 24.

In this way, water is automatically removed by suction, as well as paper being reformed by same, and consequently the suction apparatus used for forming and drying paper on cylinder may also be used for withdrawing water. The water drawing suction may also to some extent, and under certain circumstances, assist in withdrawing water from paper material.

It will be understood that changes and modifications may be made without departing from the spirit of the invention.

What I claim is:

1. A machine of the class specified having a hollow rotary member and a supporting shaft therefor, said shaft being divided into separate compartments, one of which is for forming communication to the upper part of the cylinder for withdrawing air, and the other of which is for withdrawing water

- from the lower part of the cylinder, and separate air pipes communicating with said separate compartments.
2. The combination of a hollow rotary forming member, means for withdrawing air and water from the interior of said member, a suction pipe communicating with the air withdrawing means, a separate suction pipe communicating with the water withdrawing means, and valves for regulating the suction pressures in said pipes, said pipes being connected together and a suction apparatus with which said connected pipes are in communication.
3. The combination of a hollow rotary forming member, a support therefor comprising a tubular member and pedestals, said tubular member and pedestal having air and water passages, air pipes connected with said passages and a water outlet pipe connected with the water passage.
4. The combination of a hollow rotary forming member, a support therefor comprising hollow pedestals and a tubular member, said pedestals forming separate air and water passages with said tubular member and upper air connections for both water and air passages and a lower water pipe for the lower water passage.
5. The combination of a hollow rotary forming member, supporting means therefor comprising hollow pedestals and a tubular member, said pedestals and tubular member forming separate passages for removing air and water from said forming member, and connected air pipes for the air passage and a water pipe for the water passage.
6. The combination of a hollow rotary forming member, supporting means therefor comprising a tubular member having an upper air chamber and a lower water chamber, hollow pedestals having air and water chambers communicating with said tubular member chambers, water discharge pipes at the lower end of said pedestals, and air suction connections for both air and water chambers at the top of said pedestals.
7. The combination of a hollow rotary forming member and supporting means therefor, said means comprising a tubular member having upper and lower chambers and hollow pedestals having passages connecting said chambers with exhaust connections for said upper and lower chambers and with a water pipe for the lower chamber.
8. The combination of a hollow rotary forming member and supporting means therefor, said means comprising a tubular member having an upper air chamber and a lower water chamber and hollow pedestals, said pedestals each having an air and a water passage, said air passage being at the upper side portion of said water passage, said passages communicating with said chambers and having separate air exhaust pipes and a water pipe connection for the water passage.
9. The combination of a hollow rotary forming member and supporting means therefor, said means comprising a tubular member and pedestals, each of said pedestals forming a water passage with a chamber in said tubular member and having an upper exhaust and lower pump connections and also having an upper side air passage forming an air exhaust with an air chamber in said tubular member and a second exhaust connection, said exhaust connections being adapted to vary the exhaust and being connected together to a common source of exhaust pressure.
10. The combination of a hollow rotary forming member, a supporting and exhausting means therefor comprising a tubular member and hollow pedestals, an air passage therein formed of the upper portion of said tubular member and extending into the upper side portion of said pedestals, a water passage formed of the lower portion of said tubular member and said pedestals, said pedestal having a lower water pump connection and separate variable exhaust connections for said air and water passages, said exhaust connections being connected together to a single source of exhaust pressure.
11. The combination with a hollow rotary forming member of a support therefor comprising a tubular member open at both ends and pedestals supporting the opposite ends of said member, said pedestals being hollow and having their sides fitted against the ends of said tubular member and provided with apertures corresponding with the open ends of said member and also with top apertures.
12. The combination with a hollow rotary forming member, of a support therefor, comprising a tubular member having open ends, pedestals at the opposite end of said member, said pedestals having side openings corresponding to the open ends of said member, said member having a longitudinally extending partition dividing it into longitudinal compartments and said pedestals having partitions forming continuations of said tubular member partitions, said pedestal partitions extending first horizontally from said tubular member partition and thence upwardly so as to divide the upper part of said pedestals into separate chambers.
13. The combination with a hollow rotary forming member, of a support therefor, comprising a tubular member having open ends, pedestals at the opposite end of said member, said pedestals having side openings corresponding to the open ends of said member, said member having a longitudinally extending partition dividing it into longitudinal compartments and said pedestals having partitions forming continuations

- of said tubular member partitions, said pedestal partitions extending first horizontally from said tubular member partition and thence upwardly so as to divide the upper 5 part of said pedestals into separate chambers, and pressure pipes communicating with said chambers at the upper ends of said pedestals.
14. The combination with a hollow rotary forming member, of a support therefor, comprising a tubular member having open ends, pedestals at the opposite ends of said member, said pedestals having side openings corresponding to the open ends of said 10 member, said member having a longitudinally extending partition dividing it into longitudinal compartments and said pedestals having partitions forming continuations of said tubular member partitions, said pedestal partitions extending first horizontally from said tubular member partition and thence upwardly so as to divide the upper 15 part of said pedestals into separate chambers, and pressure pipes communicating with said chambers at the upper ends of said pedestals, the pressure pipes for each pedestal being connected together and provided with valves for independent regulation.
15. The combination with a rotary forming member of a tubular support divided into air and water compartments, pedestals at the ends of said support also divided into air and water compartments communicating with the air and water compartments of 20 said support, said air and water compartments of each pedestal extending to the top of the pedestal and exhaust pipes extended to the tops of said pedestals and connected with the air and water compartments thereof.
16. The combination with a rotary forming member of a tubular support divided into air and water compartments, pedestals at the ends of said support also divided into air and water compartments communicating with the air and water compartments of said support, said air and water compartments of each pedestal extending to the top of the pedestal and exhaust pipes extended to the 25 tops of said pedestals and connected with the air and water compartments thereof, said exhaust pipes being connected with a common exhaust source and provided with separate and independent pressure regulating devices.
17. The combination of a rotary forming member, a tubular member therefor, having an open end, and provided with air and water compartments, a pedestal at the end of 30 said tubular member, said pedestal being provided with air and water chambers communicating with the air and water chambers of said support and air exhaust pipes connected with said chambers and a water outlet connected to the water chamber.
18. The combination of a rotary forming member, a tubular member therefor, having an open end, and provided with air and water compartments, a pedestal at the end of said tubular member, said pedestal being 35 provided with air and water chambers communicating with the air and water chambers of said support and exhaust pipes connected with said chambers and also connected with one another and provided with the separate pressure regulating valves.
19. The combination of a rotary forming member, a tubular member therefor, having an open end, and provided with air and water compartments, a pedestal at the end 40 of said tubular member, said pedestal being provided with air and water chambers communicating with the air and water chambers of said support and air exhaust pipes connected with said chambers and also a 45 water drain pipe connected with said water compartment.
20. The combination of a rotary forming member, a tubular member therefor, having an open end, and provided with air and water compartments, a pedestal at the end 50 of said tubular member, said pedestal being provided with air and water chambers communicating with the air and water chambers of said support and exhaust pipes connected with said chambers and also connected with one another and provided with the separate pressure regulating valves and a water drain pipe, also connected with said water compartment.
21. A machine of the class specified having a hollow rotary perforated forming member and also having a centrally arranged structure provided with a plurality of longitudinally extending compartments 55 and pedestals supporting said central structure and each provided with a plurality of chambers communicating with the compartments of said central structure, and pipes connected with said pedestals so as to communicate with the chambers thereof.
22. A machine of the class specified having a hollow perforated rotary forming member and also having a central structure provided with a plurality of longitudinally 60 extending compartments, one of said compartments being provided with means for pneumatic communication with the interior of said member and the other compartment being provided with tubular members extending downwardly in the forming member, air exhaust pipes communicating with the said compartments and liquid pipes communicating with the last mentioned compartment.
23. A machine of the class specified having a hollow perforated rotary forming member and also having a central structure provided with a plurality of longitudinally 65 extending compartments, one of said com-

partments being provided with means for pneumatic communication with the interior of said member and the other compartment being provided with tubular members extending downwardly in the forming member, air exhaust pipes communicating with the said compartments and liquid pipes communicating with the last mentioned compartment and pedestals for said central structure, said pedestals being provided each

with a plurality of chambers communicating with the compartments of said central structure, said pipes being connected with said pedestals and communicating with said central compartments through the chambers of said pedestals.

In witness whereof, I hereunto subscribe my name this 28th day of May, A. D. 1923.

EARL E. BERRY.
